US00D620109S

(12) **United States Design Patent**
Darst Rice et al.

(10) **Patent No.:** **US D620,109 S**
(45) **Date of Patent:** **** Jul. 20, 2010**

(54) **SURGICAL INSTALLATION TOOL**

(75) Inventors: **Mark W. Darst Rice**, Minneapolis, MN (US); **Daniel G. Brown**, Edina, MN (US); **Paul F. Boschert**, Minneapolis, MN (US); **Charles A. Wood**, Minneapolis, MN (US); **Ronaldo F. Carreon**, San Francisco, CA (US); **Deborah L. Hoch**, Minneapolis, MN (US); **Zachary M. Hoffman**, Bloomington, MN (US)

(73) Assignee: **Zimmer Spine, Inc.**, Minneapolis, MN (US)

(**) Term: **14 Years**

(21) Appl. No.: **29/330,097**

(22) Filed: **Dec. 29, 2008**

Related U.S. Application Data

(57) **CLAIM**

An ornamental design for a surgical installation tool, as shown and described.

DESCRIPTION

FIG. 1 is a first perspective view of a surgical installation tool to the present invention;

FIG. 2 is a second perspective view of the surgical installation tool of FIG. 1;

FIG. 3 is a front plan view of the surgical installation tool of FIG. 1;

FIG. 4 is a back plan view of the surgical installation tool of FIG. 1;

FIG. 5 is a right side plan view of the surgical installation tool of FIG. 1;

FIG. 6 is a left side plan view of the surgical installation tool of FIG. 1;

FIG. 7 is a top plan view of the surgical installation tool of FIG. 1; and,

FIG. 8 is a bottom plan view of the surgical installation tool of FIG. 1.

The broken line showing of portions of a surgical installation tool is included for the purpose of illustrating environmental structure and forms no part of the claimed design.

1 Claim, 8 Drawing Sheets
